UNITED STATES PATENT OFFICE.

ELMER G. LANTZ, OF MARION, INDIANA.

PITCHER.

SPECIFICATION forming part of Letters Patent No. 654,163, dated July 24, 1900.

Application filed February 28, 1900. Serial No. 6,810. (No model.)

To all whom it may concern:

Be it known that I, ELMER G. LANTZ, a citizen of the United States, residing at Marion, in the county of Grant and State of Indiana, 5 have invented a new and useful Pitcher, of which the following is a specification.

The invention relates to improvements in pitchers.

One object of the present invention is to 10 improve the construction of pitchers and analogous receptacles, more especially that class which is provided with a hinged cover or lid and an inner cut-off adapted to close and shut off the flow of liquid before the lid or cover 15 closes, and to provide a simple, inexpensive, and efficient device adapted to prevent the lid or cover from closing when the receptacle is in a horizontal or inclined position.

Another object of the invention is to cause 20 the drip to flow back into the receptacle and to prevent the same from coming in contact with the hinges of the lid and the cut-off.

The invention consists in the construction and novel combination and arrangement of 25 parts hereinafter fully described, illustrated in the accompanying drawings, and pointed out in the claims hereto appended.

In the drawings, Figure 1 is a vertical sectional view of a pitcher constructed in accordance with this invention, the lid or cover being closed. Fig. 2 is a similar view, the lid or cover being supported in its open position by the connecting bar or piece. Fig. 3 is a detail perspective view of the collar or band and the cut-off. Fig. 4 is a detail perspective view of the collar or band. Fig. 5 is a vertical sectional view of the top of the pitcher, the section being taken at right angles to Fig. 1.

40 Like numerals of reference designate corresponding parts in all the figures of the drawings.

1 designates a collar or band arranged on the exterior of the neck 2 of a pitcher 3 and 45 provided with an inwardly-extending annular flange 4, from the inner edge of the front portion of which extends a vertical lip or spout 5. The front portion of the inwardly-extending annular flange 4 is inclined rearward from the center of the front to the sides, 50 which are provided adjacent to the ends of the lip or spout with grooves or depressions

6, forming rear shoulders 7, and providing recesses which communicate with the interior of the receptacle. The shoulders 7 check the 55 rearward flow of the drip and cause the same to enter the receptacle. The annular flange 4 is inclined inward and downward from its outer to its inner periphery, and it slants rearward from the front of the collar or band to 60 the shoulders 7, as clearly illustrated in Fig. of the drawings. The rear portion of the annular flange is provided with a pair of upwardly-extending integral ears 8, struck up from the metal and perforated for the reception of a pintle 9, which hinges a cut-off 10 to the collar or band. The cut-off 10, which is provided at its back with depending ears 11 for the reception of the pintle 9, consists of a plate and is normally held against the lip or spout by a 70 coiled spring 12, disposed on the pintle and engaging the flange 4 and the rear edge of the cut-off. The front portion 13 of the cut-off is segmental or substantially semicircular, and the rear portion is angularly bent and upwardly 75 offset from the front portion 13 to provide a shoulder 14, which is located at the upper face of the cut-off. The said front portion of the cut-off is disposed at an inclination when the parts are arranged as illustrated in Figs. 80 1 and 2 of the drawings, and any liquid flowing backward under the cut-off will come in contact with the shoulder, which will prevent the same from flowing rearward to the hinges. The rear portion of the cut-off, which is horizontal or approximately horizontal when the lid or cover is closed and the receptacle is in an upright position, is provided with a slot 85 15, extending longitudinally of it and receiving a connecting piece or bar 16, which extends upward from the cut-off to a lid or cover 17. The lid or cover, which may be of any desired configuration, is provided at the back with a handle or thumb-piece 18, and it has depending ears 19 for the reception of 90 a pintle 20, which passes through rearwardly-extending ears 21, formed integral with and struck from the back of the collar or band. A spring 22 is disposed on the pintle 20, with its ends engaging the collar or band 1 and 100 the handle or thumb-piece 18 to hold the lid or cover normally closed.

The collar or band 1, the inwardly-extending flange 4, and the spout or lip 5, together

with the vertical and horizontal ears 19, are formed of a single piece of sheet metal, which is pressed into the shape shown in Fig. 4 of the drawings.

- 5 The connecting-piece is provided at its upper end with a perforation for the reception of a pivot 23, which passes through a pair of depending ears 24 of the lid or cover 17. The lower end 25 of the connecting-piece is reduced to form a shoulder 26 and is bent at right angles to provide an arm 27. The arm 27 forms a stop and engages the inner or lower face of the cut-off plate to enable the same to be swung upward by depressing the handle or thumb-piece 18. The pivoted connecting-piece operates by gravity to carry its shoulder 26 over the cut-off at the front end of the slot 15 when the pitcher is held in a horizontal position or at an inclination, and 15 when the connecting-piece is in engagement with the cut-off, as illustrated in Fig. 2 of the drawings, the lid or cover will be held in an open position and will be prevented from closing until the flow of the liquid contents 20 of the receptacle has been effectually cut off. When the pitcher or other receptacle is brought to an upright position, the pivoted connecting-piece swings inward and is adapted to pass downward through the slot 15 to 25 permit the closing of the lid or cover.

It will be seen that the device is exceedingly simple and inexpensive in construction and adapted to be applied to pitchers, mugs, and analogous receptacles, that a groove or 35 channel 6 is provided at the intersection of the spout or lip and the flange of the band, at each side of the latter, to conduct the drip back into the receptacle, and that the cut-off is provided with a shoulder which prevents 40 any of the liquid contents from flowing backward to the hinges or the connecting-piece and interfering with the operation of the latter. It will also be apparent that the connecting bar or piece which extends from the cut-off to the 45 lid or cover operates by gravity and that when a vessel or receptacle is held in proper position for pouring out the contents the said connecting piece or bar will engage the cut-off and prevent the cover from closing over 50 the spout or lip until the vessel is brought to an upright position.

What I claim is—

1. A device of the class described comprising a receptacle, a lid or cover hinged to the 55 receptacle, a lip or spout carried by the receptacle and located within the lid or cover,

a cut-off hingedly connected with the receptacle and closing against the lip or spout and provided with a slot, and a connecting bar or piece secured to the lid or cover and extending through the slot of the cut-off and provided with means for engaging the lower face of the latter, substantially as described. 60

2. A device of the class described comprising a receptacle, a hinged lid or cover, a hinged cut-off carried by the receptacle and located within the plane of the lid or cover and provided with a slot, and a connecting-piece pivoted to the lid or cover and extending through the slot of the cut-off and provided with a shoulder, said connecting-piece being adapted to swing backward and forward by gravity, to engage its shoulder with the cut-off and disengage it therefrom, substantially as described. 65 70

3. A device of the class described comprising a receptacle, a lid or cover hinged to the same, a cut-off hingedly connected with the receptacle and provided with a slot, and a connecting-piece carried by the lid or cover and extending through the slot of the cut-off and having a stop for engaging the lower face of the cut-off, substantially as described. 75 80

4. A device of the class described comprising a collar or band designed to be arranged 85 on the neck of a pitcher and provided with an inwardly-extending annular flange and having a lip or spout at the inner edge of the front portion thereof, said flange being inclined rearward at each side of the device and 90 provided at the ends of the lip or spout with grooves or depressions forming rear shoulders 7 to check the rearward flow of the drip and prevent the same from flowing on the rear portion of the annular flange, and a 95 cover, substantially as described.

5. A device of the class described comprising a receptacle having a lip or spout, a hinged lid or cover, a hinged cut-off, angularly bent between its ends and forming a shoulder at its upper face to stop the backward flow of a liquid, and a connecting-piece pivoted to the lid or cover and located in rear of the said shoulder and adapted to engage the cut-off, substantially as described. 100 105

In testimony that I claim the foregoing as my own I have hereto affixed my signature in the presence of two witnesses.

ELMER G. LANTZ.
